UNITED STATES PATENT OFFICE.

THOMAS BOVEY, OF CHICAGO, ILLINOIS.

AUTOMOBILE HEATER.

Application filed February 14, 1925. Serial No. 9,273.

To all whom it may concern:

Be it known that I, THOMAS BOVEY, a citizen of the United States, residing at Chicago, in the county of Cook and State of Illinois, have invented certain new and useful Improvements in an Automobile Heater, of which the following is a full, clear, and exact description, such as will enable others skilled in the art to make and use the same.

My present invention relates to automobile heaters and particularly to the type of heater, which utilizes the hot exhaust gases from the engine; although the principles of the present structure are capable of being employed in connection with heaters using electric current or other source of heat. For convenience however, the device will herein be described in connection with a heater of the first-mentioned type as showing a typical embodiment of my invention.

Heaters usually comprise a concavo-convex, or pan-shaped housing or casing that is set into a suitably shaped opening in the floor of the vehicle, the upper edges of the walls of the housing or casing being positioned substantially flush with the surface of the floor, and the upper open portion of the housing or casing is covered with a perforated top-plate or grille. The heating element, usually in the form of a radiator, communicating with the exhaust pipe from the engine, is suitably mounted in the structure thus formed, and the cool air passes into the housing or casing through the grille, circulates around or adjacent the heating element where it becomes heated and then passes out through the grille and into the vehicle so as to heat the latter. By employing a wall or partition that will surround the heating element between the same and the adjacent walls of the housing or casing, and by spacing this surrounding wall from the bottom of the latter, a better and more balanced circulation of the air is had because the cool air going down towards the bottom of the structure will be partitioned or separated from the ascending heated air. An important factor in the use of a dividing partition or wall is that the fire-hazard is practically eliminated because it provides an air-space between the heating element and the walls of the housing or casing which will prevent radiation of the heat to the housing or casing walls which are usually in

contact with the wooden floor-boards of the vehicle.

Numerous heaters are already in use which have no provision for insulating the structures from the wooden floors, and fires frequently have resulted from their use.

My present invention is designed so that a partition or auxiliary wall may be readily provided in the heater and which may be easily removed whenever desired. The structure is also designed so that it may be sold as an accessory and may be installed by a person already owning or using a heater. The principal object of my present invention is to provide a structure having the before-mentioned characteristics and advantages. Other objects reside in providing a device that is novel, dependable, and sturdy in construction, is simple in arrangement, easy to install, made of few parts and will not readily get out of order.

I prefer to accomplish the objects and carry out my invention in substantially the manner hereinafter fully described and as more particularly pointed out in the claims, reference being now made to the accompanying drawings that form a part of this specification.

In the drawings:—

Figure 1 is a longitudinal section of a heater showing my invention installed therein.

Figure 2 is a perspective of the partition or auxiliary wall removed from the housing or casing.

Figure 3, is a side elevation of one of the devices for supporting and maintaining the partition in place.

Figure 4, is a top plan of the device shown in Figure 3.

Figure 5 is a transverse section of the heater parts showing them separated and about to be assembled.

Figure 6 is a fragmentary detail, partly in transverse section and enlarged, showing the manner of mounting the partition.

Figure 7 is a perspective of one of the positioning or supporting devices.

Figure 8 is a perspective of a modified form of positioning and supporting devices.

In the drawings, I have employed similar reference characters to designate the same parts wherever they appear throughout the several views. Referring to Figures 1 and 5 it will be seen the heater structure com-

prises a concavo-convex, pan-shaped housing or casing 10 preferably formed of sheet-metal with lateral marginal flanges 11 extending horizontally from the upper edges 5 of the walls thereof, which flanges are adapted to rest upon the surface of the floor 12 of the vehicle when the body of the housing or casing is positioned in an opening made in the floor in the manner illustrated in Figure 6 of the drawings. The heating element 13, in the present instance a tubular radiator coil, is suitably mounted within the housing or casing 10, and a perforated top-plate in the form of grating or 10 grille 14 covers the upper open portion of the housing or casing above the heating element 13 so that the occupant's feet are protected from the heating element and articles are prevented from falling into the housing or 15 casing; while at the same time facilities are provided whereby the air is taken into the heater and after circulating around or about the radiator is discharged in a heated condition into the vehicle. The housing or casing 20 10 and the grating or grille 14 are maintained in assembly and the whole structure is secured to the vehicle floor by means of threaded bolts 15 that pass through the marginal rims of the grille, the flanges 11 25 of the housing, and through the vehicle floor and are clamped to the latter by nuts 16 screwed upon the lower extended ends of the bolts.

The partition or auxiliary wall, heretofore referred to preferably comprises a rectangular-shaped element consisting of transverse end walls 17 and longitudinal side walls 18 all of which are made from sheet-metal or other desirable material, and said 30 walls may be separate parts suitably joined together at the corners of the partition, or they may all be formed from a single strip of material bent to the desired shape between its ends and the ends secured together 35 in any manner. The proportions and shape of the structure is substantially the same as the walls of the housing or casing but the partition is of less length, width and height than the housing or casing so that it may 40 be fitted between the walls thereof and said heating element. I prefer not to fasten or secure this partition to any of the adjacent parts of the heater as special brackets or other securing devices would be required to 45 do so which would materially add to the cost, but it is essential that said partition be spaced from the bottom of the housing or casing so as to permit the air which enters the heater through the perforations 50 along the edges or marginal portions of the grille to pass downwardly and under the lower edges of the partition and pass upwardly and out of the heater upon the opposite sides of the partition. The means for 55 mounting this partition element is in the 60

form of attachable, preferably springy or yielding supports, which consists of a length of wire that is bent mediate its ends into two coils 19, 19, that are connected by the curved portion 20, which provides a concave 70 seat for the edge of the partition and the remaining portions of the wire extend obliquely to each other and tangent to their respective coil 19 to provide oppositely diverging legs 21, 21 the whole support being 75 of an inverted V-shape or U-shape. I prefer to employ a plurality of these supports, and in the drawings I have illustrated the use of two of them upon each longitudinal wall of the partition, but it will be appreciated that both the number and the disposition of the supports is optional according to the service required. The coils 19 are, if desired spaced a slight distance apart or they may be in contact with each other as 80 desired, and when in use the lower edges of the partition wall are inserted between the coils of each support so that the lower edges of the partition will preferably rest in the seat formed by the connecting segment 20 85 before mentioned. The fit between the respective parts is such sufficient friction is created to prevent accidental dislodgment of the supports during assembly of the heater or when in use. The partition thus provided 90 with the spring supports is positioned in the housing or casing prior to the placing of the grating or grille on the latter. When the partition has been placed in the housing or 95 casing with the supports resting on the bottom of the latter the upper edge of the partition will project slightly above the horizontal plane of the top edges of the walls of the casing so that the grille is placed in contact with the upper edge of the walls of 100 the partition and by a slight pressure forced downwardly against the spring action of the support until the margins of the grille are in desired relation to and in contact 105 with the flanges 11 of the housing or casing, 110 whereupon the whole structure may be secured together and fastened to the floor of the vehicle by the bolts and nuts as heretofore described. Thus the partition is yieldingly maintained in position, in contact 115 with the underside of the grille and is spaced from the bottom of the casing by means of the spring support, and in order to permit of a smooth contact between the ends of the legs 21 and the bottom member 120 of the casing the lower end portions of the legs are bent in short reverse curves 22 so that the convex portions of the curves will rest upon the bottom of the casing as shown.

It is obvious that other forms of the support for the partition may be provided, such for example as that illustrated in Figure 8 of the drawings, which comprises a strip of thin metal bent an inverted V-shape or U-shape to provide converging legs 23, 23, and 125 130

at the apex of the support the seat, in the form of a longitudinal slot 24, is provided to receive the lower edge of the partition wall, while the lower end portion of the legs are 5 provided with reverse bends 25 to rest upon the bottom member of the casing.

From the foregoing it will be seen that I have provided a partition that may be readily assembled with a heater already in use, 10 and while this partition when assembled in the heater not actually secured to the heater parts nevertheless the manner of mounting the same is such that it is, to all intents and purposes rigidly related to the casing and 15 grille, and it will perform all the functions of a partition that is secured to and depending from the grille, or which may be otherwise mounted in the casing so that the air will pass under the same to the heating element. 20

What I claim is:—

1. A removable partition for heaters comprising a suitably shaped strip, and supports extending from an edge thereof whereby to 25 space said strip from the bottom of the heater.

2. A removable partition for heaters comprising a suitably shaped strip, and yieldable supports extending from an edge thereof 30 of whereby to space said strip from the bottom of the heater.

3. A removable partition for heaters comprising a suitably shaped strip, and supports extending from an edge thereof and removably secured thereto whereby to space said 35 strip from the bottom of the heater.

4. A removable partition for heaters comprising a suitably shaped strip, and yieldable supports extending from an edge thereof 40 and removably secured thereto whereby to space said strip from the bottom of the heater.

45 5. A removable partition for heaters comprising a suitably shaped strip, and means for supporting the same in spaced relation with the bottom of the heater consisting of a length of yieldable metal bent substantially inverted V-shape and formed at its apex to receive the lower edge of said strip.

50 6. The combination with a heater includ-

ing a casing, a perforated top-plate, and a heating element within said casing, of a partition consisting of a hollow rectangular frame interposed between the heating element and the walls of the casing, and supports extending from the lower edges of said frame whereby to space the same from the bottom of the casing. 55

7. The combination with a heater including a casing, a perforated top-plate, and a 60 heating element within the casing, of a partition consisting of a hollow rectangular frame interposed between the heating element and the walls of the casing, and yieldable supports extending from the lower 65 edges of said frame whereby to space the same from the bottom of said casing and yieldingly maintain the upper edge of said frame in contact with said top-plate.

8. The combination with a heater including a casing, a perforated top-plate, and a heating element, within the casing, of a partition consisting of a hollow rectangular frame interposed between the heating element and the walls of the casing, and yieldable supports each consisting of a length of 70 yieldable metal bent substantially inverted V-shape and formed at its apex to receive the lower edge of frame, whereby to 75 space the latter from the bottom of said casing.

9. The combination with a heater including a casing, a perforated top-plate, and a heating element within the casing, of a partition consisting of a hollow rectangular 80 frame interposed between the heating element and the walls of the casing, and yieldable supports each consisting of a length of 85 spring wire formed substantially inverted V-shape and provided at its apex with a double coil between the convolutions of which the lower edge of said frame is positioned whereby said frame is supported in spaced 90 relation with the bottom of the casing and is yieldingly maintained in engagement with 95 said top-plate.

Signed at Chicago, in the county of Cook, and State of Illinois this 26th day of January, 1925.

THOMAS BOVEY.
